UNITED STATES PATENT OFFICE.

VIRGIL L. BEAUCHAMP, OF EVANSTON, ILLINOIS.

POWDER-BOX.

1,389,288.

Specification of Letters Patent. Patented Aug. 30, 1921.

Application filed May 5, 1919. Serial No. 294,747.

To all whom it may concern:

Be it known that I, VIRGIL L. BEAUCHAMP, a citizen of the United States, and resident of Evanston, county of Cook, and State of Illinois, have invented certain new and useful Improvements in Powder-Boxes, of which the following is a specification, and which are illustrated in the accompanying drawings, forming a part thereof.

10 The object of the invention is the provision of a powder box and puff holder which shall be more convenient for use than articles of the sort heretofore known.

In the accompanying drawings:

15 Figure 1 is a plan view from the puff compartment with the closure removed;

Fig. 2 is a plan view from the powder compartment with the cover removed;

20 Figs. 3 and 4 are central longitudinal sections taken on lines 3—3 and 4—4 of Fig. 1, respectively, Fig. 3 showing the cover and closure for the compartments in place,

Fig. 5 is a perspective view of the box, and

25 Fig. 6 is a view corresponding to Fig. 1, illustrating a modification.

As illustrated, the box comprises a cover 10 which cover is preferably provided with a mirror, as 11, held in place by the metal

30 of the cover being turned thereabout, as indicated at 12. The sides of the box are indicated at 13 and the bottom at 14, which bottom is perforated or foraminous, as indicated at 15. The sides of the box are ex-

35 tended beyond the bottom, as indicated at 16 thus providing a recess below the bottom of the box, which recess serves as a compartment for the reception of the powder puff 17, which is preferably secured to the clo-

40 sure of the puff compartment, as 18. Lying closely adjacent to the bottom of the box is a reciprocating plate 19, which is foraminous or perforated, as indicated at 20.

This plate has integral therewith a stem 21

45 projecting to the exterior of the box, the end thereof being provided with a button 22. To retain the sliding plate in place and

50 guide the reciprocation thereof, there is provided a retaining plate 23 having a cut out portion 24, opposite the location of the plate and flanges as 25, 26, struck up therefrom to retain the plate in contact with the bottom. The portion of the plate surrounding the sliding plate 19 lies in the same

55 plane with the sliding plate and in contact with the bottom. At 27 a portion of the re-

taining plate is cut away and in the space left by the cut away portion projection 21 of the sliding plate lies and slides.

The portion of the retaining plate below the line of 28, Fig. 1, is struck out from the plane of the retaining plate to the level of the retaining flanges 25 and 26 with the exception of a small portion 29, which lies in contact with the bottom of the box and the end 30 of this portion serves as a stop for the sliding plate. Rivets 31 are shown which rivets are passed through the retaining plate and through the bottom of the box to hold the parts in assembled position.

A spring 32 is provided to press the sliding plate to one limit of its travel and the plate is caused to reciprocate against the pressure of this spring by pressing upon the button 22 upon the exterior of the box. Spring 32 lies in the space provided by the striking out of the portion below line 28, Fig. 1, and its consequent separation from the bottom of the box.

Spring 32 comprises an upwardly bowed central portion the opposite ends of which portion are each extended into a downwardly convex curve and then an upwardly convex curve, the portions at the outer side of the last named curves comprising oppositely directed substantially horizontal extremities. The extremities are shown as seated on relatively diverging portions of the walls of the box which divergence is provided by the curvature of the side walls of the box. It is found that this form of spring may be placed in the box, under initial compression, without special preparation of the box wall for seating the ends of the spring and will function without movement of the ends of the spring from their first position. The portions of the spring adjacent the extremities by the flexibility of the successive curves are permitted to have a hinge-like action about the extremity without movement of the end of the spring relative to the wall. The curves lying in one plane and the material of the spring being of less thickness than plate 19, the spring works freely in the recess provided for it.

At each corner of the sliding plate, as indicated at 33, the retaining plate is cut away to permit the escape of any powder which may be trapped against the bottom of the box and in the space about the sliding plate. The cover of the box, as well as the closure for the puff compartment, are preferably

formed in the shape shown and fit within the periphery of the sides of the box, as indicated at 34.

In the modification of Fig. 6 the sliding plate is of the same shape and operates in the same manner and is pressed by the same sort of a spring as in the modification of Figs. 1 to 4. However, instead of the flanges 25, 26, of the first modification, the retaining plate is formed as a complete and unbroken disk with the exception of a rectangular opening, as 35, which exposes the perforations in the sliding plate. Lying in contact with the bottom of the box are three members, two of these members, indicated at 36, are of such a form as to surround the sliding plate 19 and the projection 21 thereof to the exterior of the box. The third member lying against the bottom of the box is indicated at 37, and serves as a stop for the plate in its reciprocation.

These members, 36 and 37, are substantially the thickness of plate 19 and in assembly are placed against the bottom of the box in the relation shown. The plate 19 is laid into the space left by the form of members 36 and the retaining plate or disk is laid over the whole and secured to the members and to the bottom of the box, as by rivets 38. Therefore, members 36 and 37 serve to space the retaining plate away from the bottom of the box in this modification, as well as for guides and a stop for the reciprocation of plate 19.

Preferably I provide openings, as 39, in the retaining plate in the modification of Fig. 6, to allow the escape of any powder which might find access to the recess occupied by spring 32.

When the parts are assembled, as indicated in Fig. 3, if the powder compartment be held downward and the plate reciprocated, powder will be deposited on the puff when the puff and puff compartment closure may be removed and the puff used without waste of the powder.

I claim as my invention:

1. A powder box having a powder compartment, a puff compartment, a closure for said puff compartment, a puff secured to said closure, a foraminous partition separating said compartments, a reciprocating foraminous plate lying closely adjacent said partition, a retaining member having a cut-out portion adjacent the central portion of said plate, means to guide the reciprocation

of said plate and to space said retaining plate from said bottom, and means external of the box to reciprocate said plate.

2. A powder box comprising a powder compartment, a puff compartment, a foraminous partition separating said compartments, a perforated reciprocable plate lying closely adjacent said partition having an extension to the exterior of the box, a spring pressing the plate to one limit of its travel, guide elements substantially surrounding said plate on three sides, and a retaining plate spaced away at certain portions from said partition so as to overlap the edges of said reciprocable plate and to form a recess for concealment of said spring.

3. A powder box comprising a powder compartment, a puff compartment, a foraminous partition separating said compartments, a perforated reciprocable plate lying closely adjacent said partition and having an extension to the exterior of the box, a spring pressing the plate to one limit of its travel, guide elements substantially surrounding said plate on three sides, a retaining plate spaced away at certain portions from said partition so as to overlap the edges of said reciprocable plate and to form a recess for concealment of said spring, portions of said retaining plate cut away over said recess to permit escape of trapped powder.

4. A powder box comprising a foraminous bottom, a perforated reciprocable plate lying against said bottom, guide and stop members substantially equal in thickness to said plate arranged thereabout, a spring of less thickness than said plate pressing said plate toward one limit of its travel and a retaining plate cut away at its central portion to expose the perforations, superimposed on said guide and stop members and overlapping the edges of said reciprocable plate and concealing said spring.

5. A powder box comprising a foraminous bottom, a perforated reciprocable plate co-acting therewith and surrounded by walls having relatively diverging portions, a spring bowed upwardly at its center to act on said plate the ends of said spring extending outwardly and seating on said diverging walls, the portions of said spring at each end of the bowed portion curved upwardly then downwardly to join the outwardly directed extremities.

VIRGIL L. BEAUCHAMP.
